UNITED STATES PATENT OFFICE

CHRISTIAN C. KOELN, OF ST. LOUIS, MISSOURI, ASSIGNOR, BY MESNE ASSIGNMENTS, TO DAVIS BORING TOOL COMPANY, OF ST. LOUIS, MISSOURI, A CORPORATION OF MISSOURI

EXPANSION BORING TOOL

Application filed February 23, 1924. Serial No. 694,700.

This invention relates to boring tools and more particularly to such tools of the expansion type.

One of the objects of this invention is to provide a boring tool of improved construction in which the expanding cutters or blades may be positively adjusted for expansion and accurately set at the required adjustment.

10 Another object of this invention is to provide an improved boring tool, which may be economical to manufacture, simple to operate, and rugged and durable in service.

Further objects will appear from the detailed description taken in connection with the accompanying drawing, in which:

Figure 1 is a plan view of the head of a boring tool embodying this invention;

Figure 2 is a section on line 2—2, Figure 1;

Figure 3 is a detail showing the method of securing the cutters;

Figure 4 is a view similar to Figure 1 showing another embodiment of this invention;

Figure 5 is a perspective detail view of the adjusting wedge shown in Figure 4; and

Figure 6 is a detail of the clamping device of Figure 4.

30 Referring now to the accompanying drawing, 1 designates the boring bar which may be of any well known construction. The head 2 of this bar is pierced by a transverse opening 3 which is oblong in general cross-section having rounded ends as shown in dotted lines in Figure 1 and which extends transversely through the head 2 from one side to within a short distance of the other.

40 At this other side the opening 3 is reduced in size so as to form a shoulder 4 having an oblong contour to correspond with that of the rest of the opening. At the center of the opening 3 on this same side, the size thereof is further reduced so as to provide a circular shoulder 5. From the shoulder 5 the opening is circular and extends through the head. At the side of the head opposite the shoulders 4 and 5 the opening

50 is enlarged to form a third shoulder 6, the

enlargement having an oblong outline to correspond with the perforation 3.

The perforation 3 is adapted to provide a guide for an adjusting element 7, the head 8 of which has an oblong contour adapted 55 to fit the perforation 3 for sliding movement therein and adapted at the extremity of its upward travel, Figure 2, to engage the shoulder 4 which limits its movement in that direction. The element 7 has an oblong 60 wedge shape below the head 8 thereof and is provided at its lower extremity with a base 9 of a size and shape to fit the perforation 3 for sliding movement therein in a manner similar to the head 8. 65

The adjusting element 7 is provided with a threaded opening centrally thereof adapted to receive an adjusting screw 10 having a graduated head provided with a wrench-socket 11. The screw 10 is provided, a little 70 below the head thereof, with a flange 12 adapted to engage the shoulder 5 to bear thereagainst when operating to force the wedge downwardly for adjustment. The adjusting element 7 may be raised or lowered by turning the screw 10 in one direction or another and the amount of adjustment 75 may be accurately set off on the graduated head.

The adjusting element 7 is inserted in 80 the guide opening 3 from the bottom thereof, Figure 2. After inserting the element 7 the opening is closed by means of a plug 13 having a contour corresponding to that of the opening. The plug 13 may be fixed 85 in place against the shoulder 6 by peening over the edges of the opening or other suitable means. The plug 13 carries an adjustable pilot 14 screw-threaded for adjustment in the plug 13 as shown in Figure 2. 90 The pilot 14 engages a socket 15 in the element 7 in which it slides as said element moves during adjustment. The pilot 14 also acts as a stop to limit the downward 95 movement of the adjusting element 7, being adjustable for that purpose by screwing in or out in the plug 13.

The head 2 is further provided with transverse guide slots adapted to receive a pair of cutter blades 16 having their inner 100

edges beveled to correspond with the wedge faces of the adjusting element 7 as illustrated in Figure 2. The cutters 16 are slideable in and out in the head 2 for adjustment under the influence of the element 7 and are provided with transverse grooves 17 adapted to be engaged by set screws 18 threaded into the head 2. The grooves 17 are V-shaped and have an angle corresponding with that of the cone-points 19 of the set screws 18. The grooves 17 are somewhat off-set with respect to the centers of the screws 18 as illustrated in Figure 3. Thus when the screws are set down into the grooves 17, they will bear against only the rear side of said grooves so as to force the cutters back against the shoulder 20 at the rear of the guide slot. The cutters are thus not only clamped against alterations of their positions but are seated firmly against the shoulder 20 so as to insure parallelism of their cutting edges and to support the same against the thrust incident to the boring operation.

It will be noted that when the set screws 18 are loosened the two cutters may be positively and accurately adjusted outwardly by turning the screw 10 so as to move the adjusting element 7 downwardly with the screw. The element 7 is guided in the guide perforation 3 both by its head 8 and its base 9 so that an accurate rectilinear movement will be assured. The element 7 is, therefore, at all times accurately centered whereby it is insured that the cutters 16 will be equally adjusted. Such adjustment is then rendered permanent by tightening the set screws 18.

In the embodiment illustrated in Figure 4 the adjusting element 70 may be provided with dove-tailed grooves 21 adapted to be engaged by corresponding dove-tailed projections on the cutters 160 so that by adjusting the element 70 up or down, the cutters may be projected or retracted as desired.

In this embodiment also the set screws 180 may be provided with cone-shaped shanks 190 adapted to engage a correspondingly beveled edge of a clamping bar 22. The bar 22 is suitably recessed to receive a pair of Woodruff keys 23 adapted to bear each against the rear edge of one of the cutters 160. When the set screws 180 are screwed down the action of the shanks 190 against the beveled edge of the clamping bar 22 will force said bar to the left, Figures 4 and 6, so as to force the cutters to the left against the shoulder 24 at the front of the guide slot. During this operation the Woodruff keys 23 may turn in their sockets so as to provide an even bearing against the cutters regardless of any tilting of the bar 22 which may be occasioned by unequal adjustment of the two screws 180. These

screws may be provided with enlarged heads 25 adapted to take under the bar 22 so as to keep the screws from falling out when loosened.

It will be noted that this invention provides a simple and effective device for adjusting expandible boring tools. The adjusting elements 7 and 70 being guided in the boring head are adapted to equally and simultaneously adjust the cutters for expansion. The construction is simple and rugged and economical to manufacture. The oblong shape of the wedge provides an extended bearing against the inner edges of the cutters so as to insure their remaining in parallelism and to take any radial thrust incident to the cutting operation.

It is obvious that various changes may be made in details of construction without departing from the spirit of this invention; it is, therefore, to be understood that this invention is not to be limited to the specific details shown and described.

Having thus described the invention, what is claimed is:

1. An expandible boring tool, comprising, a bar having an oblong guideway therein and extending therealong, a long cutter blade guided for movement in said bar transversely of said guideway, an oblong adjusting element having an oblong head and an oblong base, each working in said guideway and having a wedge between said head and base adapted to have a substantially continuous bearing against a long side of said blade, means to interconnect said wedge and blade whereby movement of said wedge will move said blade in either direction, and means for adjusting said element.

2. An expansion boring tool comprising, a bar having an oblong guideway extending therealong, a long cutter blade guided for movement in said bar transversely of said guideway, an oblong adjusting element working in said guideway, said element having spaced guide parts and an intermediate adjusting part engaging said blade for an extended distance therealong, and means for adjusting said element.

In testimony whereof I affix my signature this 30th day of January, 1924.

CHRISTIAN C. KOELN.
